(57) **CLAIM**

The ornamental design for a portable power charger, as shown and described.

DESCRIPTION

FIG. 1 is a front, right and bottom perspective view of a portable power charger, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right and bottom perspective view of a second embodiment of a portable power charger.

FIG. 10 is a rear, left and top perspective view of the second embodiment of the portable power charger of FIG. 9.

FIG. 11 is a front elevation view of the second embodiment of the portable power charger of FIG. 9.

FIG. 12 is a rear elevation view of the second embodiment of the portable power charger of FIG. 9.

FIG. 13 is a left side elevation view of the second embodiment of the portable power charger of FIG. 9.

FIG. 14 is a right side elevation view of the second embodiment of the portable power charger of FIG. 9.

FIG. 15 is a top plan view of the second embodiment of the portable power charger of FIG. 9; and,

FIG. 16 is a bottom plan view of the second embodiment of the portable power charger of FIG. 9.

The broken lines shown in the drawings are included for the purpose of illustrating portions of the portable power charger that form no part of the claimed design.
